BIT FORMING MACHINE

Filed Aug. 30, 1927

UNITED STATES PATENT OFFICE

JEREMIAH V. GUSTIN, OF LITTLE ROCK, ARKANSAS

BIT-FORMING MACHINE

Application filed August 30, 1927. Serial No. 216,452.

This invention relates to a bit forming machine.

Some of the objects of the present invention are: to provide a machine of the indicated character with which uniform shaped bits of comparatively superior and refined construction may be produced expeditiously and for sharpening used bits of uniform shape; to provide means in the machine for accommodating stock or used bits of different sizes; to provide means in the machine for cutting off any surplus material or metal in forming a bit; and to provide a machine which is durable yet light in weight, and which is easy to operate.

The nature of the invention and its distinguishing features and advantages will appear when the following specification is read in connection with the accompanying drawing, in which

Figure 1 is an end elevation of the machine embodying the features of the present invention; the lower roll being shown partly in section.

Fig. 2 is a side elevation.

Fig. 3 is an enlarged sectional view of portions of the rolls of the machine and illustrating the relationship of parts immediately prior to the application of pressure to the stock for forming a bit thereon.

Fig. 4 is a sectional view illustrating the progression of the rolls to the point of completion of the bit.

Fig. 5 is a sectional view illustrating the manner in which the stock is ejected after the bit has been formed.

Fig. 6 are views of a piece of stock before and after being acted on by the machine.

Referring now more particularly to the drawing, it will be apparent that, in the illustrated embodiment, the machine includes a supporting structure comprising a base 10 and side frames 11 rigidly secured to the base 10. Shafts 12 and 13 are respectively mounted in suitable bearings 14 and 15 on each of the frames 11. The shaft 12 is the drive shaft and motion is transmitted from the shaft 12 to the shaft 13 by spur gears 16 and 17 respectively keyed to

the shafts 12 and 13. The axes of the shafts 12 and 13 are disposed in the same vertical plane. It will be apparent that the shafts 12 and 13 will rotate in opposite directions. A pair of rolls 18 and 19 are respectively keyed to the shafts 12 and 13. The roll 18 is equal in diameter to the diameter of the roll 19. The roll 18 consists of two sections, a section 20 and a section 21. The section 20 has a rim or circumferential tongue 22, and a dovetail recess 23 which opens through the periphery of the rim or tongue 22. Arranged in the recess 23 is a tempered die 24 which is of a shape to conform to the shape of the recess 23 so as to be held therein. The die 24 has a convexed or arcuate stock or work engaging face 25 which juts out from the peripheral face of the rim 22. The die 24 is also tapered longitudinally as shown in Fig. 1. The sections 20 and 21 of the roll 18 are securely held together by suitable fastening elements 26. The roll 19 consists of sections 27 and 28 which are also held together by suitable fastening elements 29. The section 27 has a recess 31. Arranged in the recess 31 is a tempered die 32. The die 32 has relatively angularly disposed flat stock or work engaging faces 33 and 34. The die 32 also has a recess 35 which presents a transverse straight cutting edge 36. The die 32 also has a groove which receives a portion of a bolt 37, the latter serving to hold the die 32 in place.

In order to hold a piece of stock, such as the piece designated 38, in place to be acted on by the dies 24 and 32 to form a bit, the section 27 of the roll 19 is provided with a transverse recess 39. One end of the recess opens through the peripheral face of the section 27 adjacent the die 32. The opposite end of the recess 39 also opens through the peripheral face of the section 27. Arranged for sliding movement in the recess 39 is an ejector 40. One end of the ejector is adapted to act on one end of the stock 38 and the

opposite end of the ejector is adapted to be acted on by the rim or tongue 22. The ejector is returned to a normal position by means which consists of a stud 41 carried by the section 27 and extending into a slot 42 in the ejector 40, and a retractile spring 43 having one end connected with the stud 41 and the opposite end thereof connected with the ejector 40. In order to change the normal position of the ejector to accommodate stock or used bits of different lengths there is provided means consisting of a screw bolt 44 held against longitudinal movement but permitted to have rotational movement by a collar 45 on the bolt 44, and a nut 46 in threaded engagement with the bolt, the latter serving as a stop or abutment encountered by a lug 47 on the ejector 40. The bolt 44 has a cross sectionally square end 48 which accommodates a suitable tool for effecting the turning movement of the bolt 44 to change the position of the nut 46. It will be apparent that by changing the position of the nut 46 the normal position of the ejector 40 may also be changed. It will also be apparent that the ejector 40 serves not only to positively eject the stock out of the recess 39 after the bit has been formed thereon, but also serves as an abutment to limit the extent to which pieces of stock of the same length may be successively inserted into said recess, to thus insure the production of tools of uniform size and shape.

From the foregoing it will be apparent that when a piece of stock, such as the piece 38 is arranged in the recess 39 that the inner end of the stock will abut one end of the ejector 40. In this way the stock will be held in place against movement. It is to be understood that the stock will be heated prior to its introduction into the recess 39. As the rolls 18 and 19 rotate, there will come a time when the dies 24 and 32 will come to a coacting relationship to apply pressure to the end of the stock jutting from the recess 39, and as a consequence a bit will be formed on the end of the piece of stock. Such bit is designated 49. Due to the fact that the dies 24 and 32 are tapered longitudinally the bit will also be tapered as shown most clearly in Fig. 6. The surplus metal, if any, will be cut off by the cutting edge 36 thereby insuring a clean, straight and sharp edge. The surplus metal finds its way into the recess 35 and is thus kept from getting between the rolls. As the rolls 18 and 19 continue to rotate, there comes a time when the projecting end of the ejector 40 is encountered by a portion of the rim or tongue 22, and as a consequence the ejector is moved, and in turn moves or ejects the completed bit from the recess 39. When pressure on the ejector is relieved, the spring 43 automatically returns the ejector 40 to its normal position 65 in which the lug 47 engages the nut 46. This

expedient increases the output of the machine.

In the present instance there are two sets of dies 24 and 32 and stock ejecting mechanisms. It is to be understood that the pair of dies and ejecting mechanism in each case will be similar.

It is also to be understood that used bits of uniform shape may be arranged in the recess 39 to be acted on by the dies 24 and 32 for the purpose of sharpening the bits.

I claim:

1. In a bit forming machine, a pair of oppositely rotatable rolls, one of said rolls having a recess therein for the reception of stock from which a bit is to be formed, coacting dies respectively carried by said rolls for exerting pressure on the stock in the rotation of the rolls to form the bit, and means carried by the stock receiving roll operated by the other roll in the rotation of both rolls for ejecting the stock from the recess after the bit has been formed.

2. In a bit forming machine, a pair of oppositely rotatable rolls, one of said rolls having a recess therein for the reception of stock from which a bit is to be formed, coacting dies respectively carried by said rolls for exerting pressure on the stock in the rotation of the rolls to form the bit, and means operated by one roll in the rotation of both rolls for ejecting the stock from the recess after the bit has been formed.

3. In a bit forming machine, a pair of oppositely rotatable rolls, one of said rolls having a recess therein for the reception of stock from which a bit is to be formed, coacting dies respectively carried by said rolls for exerting pressure on the stock in the rotation of the rolls to form the bit, and means carried by one roll and operated by the other roll in the rotation of both rolls for ejecting the stock from the recess after the bit has been formed.

4. In a bit forming machine, a pair of oppositely rotatable rolls, one of said rolls having a recess therein for the reception of stock from which a bit is to be formed, coacting dies respectively carried by said rolls for exerting pressure on the stock in the rotation of the rolls to form a bit, an ejector arranged in said recess for sliding movement, said ejector having a portion which acts on the stock and a portion which is acted on by one of the rolls in the rotation of both rolls to move the ejector in one direction to eject the stock from the recess, and means which operates automatically to return the ejector to its normal position.

5. In a bit forming machine, a pair of oppositely rotatable rolls, one of said rolls having a recess therein for the reception of stock from which a bit is to be formed, coacting dies respectively carried by said rolls

for exerting pressure on the stock in the rotation of the rolls to form a bit, an ejector arranged in said recess for sliding movement, said ejector having a portion which acts on the stock and a portion which is acted on by one of the rolls in the rotation of both rolls to move the ejector in one direction to eject the stock from the recess, means which operates automatically to return the ejector to its normal position, and means for changing the normal position of the ejector.

6. In a bit forming machine, a pair of oppositely rotatable rolls, one of said rolls having a recess therein for the reception of stock from which a bit is to be formed, co-acting dies respectively carried by said rolls for exerting pressure on the stock in the rotation of the rolls to form the bit, and adjustable means for ejecting the stock from the recess after the bit has been formed.

7. In a bit forming machine, a pair of oppositely rotatable rolls, one of said rolls having a recess therein for the reception of stock from which a bit is to be formed, co-acting dies respectively carried by said rolls for exerting pressure on the stock in the rotation of the rolls to form the bit, and means on the stock roll adapted to abut one end of the stock during the bit forming operation, and said means also being operated by the other roll to eject the stock from the recess after the bit has been formed.

8. In a bit forming machine, a pair of oppositely rotatable rolls, one of said rolls having a recess therein for the reception of stock from which a bit is to be formed, co-acting dies respectively carried by said rolls for exerting pressure on the stock in the rotation of the rolls to form the bit, means which serves to abut one end of the stock during the bit forming operation, said means also serving for ejecting the stock from the recess after the bit has been formed, and means for adjusting the first mentioned means for the purpose of accommodating stock of various lengths for the purposes specified.

9. In a bit forming machine, a movable stock carrier, means on the carrier adapted to abut one end of the stock during the bit forming operation, said means also being operable to eject the stock from the carrier after the bit has been formed, and means for adjusting the first mentioned means for the purpose of accommodating stock of various lengths.

10. In a bit forming machine, a die roller having a transverse recess therein for the reception of a piece of stock, a member arranged in said recess which in its normal position abuts one end of the piece of stock during the bit forming operation, yieldable means constantly acting on said member to

hold the member in a normal position, said member adapted to be acted on to move the same to eject the stock after the bit has been formed.

Signed at Little Rock, in the county of Pulaski and State of Arkansas, this 23d day of August, A. D. 1927.
